UNITED STATES PATENT OFFICE.

JAMES R. ROBINSON AND JOHN F. SUGRUE, OF ENNIS, TEXAS.

METAL RAILWAY-TIE.

No. 914,077.

Specification of Letters Patent.

Patented March 2, 1909.

Application filed September 11, 1908. Serial No. 452,544.

To all whom it may concern:

Be it known that we, JAMES R. ROBINSON and JOHN F. SUGRUE, citizens of the United States, and both residents of Ennis, in the 5 county of Ellis and State of Texas, have invented a new and Improved Metal Railway Tie, of which the following is a full, clear, and exact description.

This invention relates to certain improvements in metal railway ties constructed from 10 one piece of metal and provided with integral clamps for the rails.

The purpose of the invention is to provide for the cheapest possible construction of such 15 a tie, without the sacrifice of strength, and to render the tie more or less yielding between the rails, the material cut away in the side flanges to accomplish such a result, being utilized as stays or braces.

20 It is a further purpose of the invention to locate and lock braces immediately under the rails, in such manner as to strengthen the tie, and also to so sink the braces into the ballast as to hold the rails absolutely in alignment. The braces are so placed as to avoid 25 any possibility of water getting into the incisions in ballast made by the brace and causing the track to churn.

It is a further purpose of the invention to 30 construct a metal tie wherein no bolts are required, and wherein the side flanges are inclined downward and outward in opposite directions, affording a maximum bearing surface on the ballast and wherein by cutting 35 the side flanges away at the central portion of the tie, such elasticity is given to the track as to absolutely prevent it from becoming "center bound".

The invention consists in a device of this 40 character comprising a metal tie made from one piece of metal, having outwardly flaring side members, the tie being more or less yielding at its center, and provided with integral clamps for the rails and braces immediately 45 below the rails, secured to the tie in such manner as to preclude the use of bolts and nuts.

The invention also contemplates novel features of construction and combination and 50 arrangements of parts, whereby certain important advantages are attained and the device is rendered simpler and less expensive and otherwise better adapted and more con-

venient for use, as will be hereinafter fully set forth. 55

The novel features of the invention will be carefully defined in the claims.

In said drawings, Figure 1 is a sectional side elevation of the improved tie and a section through rails laid thereon; Fig. 2 is a plan 60 view of the tie and a portion of a rail clamped thereon; and Fig. 3 is an enlarged transverse section taken practically on the line 3—3 of Fig. 2.

Like characters of reference indicate corresponding parts in all the views. 65

The tie is constructed from one rectangular piece of metal, and comprises a flat top section 10 and side flanges 11 that extend downward from the top section 10, flaring outwardly or inclining downwardly in opposite directions. The flanges 11 are cut away at 70

their central portions to produce recesses 12, whereby without materially weakening the tie, sufficient elasticity is afforded between 75 the rails A, supported by the tie, to absolutely prevent the track from being "center bound". The diverging flanges 11, give the tie a maximum of bearing on the road bed and such purchase upon the ballast as to 80 insure a firm and steady support for the rails.

The material removed from the central portion of the flanges 11 is utilized to construct braces 13. The braces extend from one flange 11 to the other adjacent to the ends 85 of the tie and beneath the rails. The material displaced in producing the openings 14 in the top is bent upward at the ends of the openings, forming clamping lugs 15, which when the rails A are placed upon the tie, are 90 forced downward to clamping engagement with the flanges of the rails, as is shown in Fig. 1. The clamping lugs may be duplicated if desired.

The braces 13 extend from top to bottom 95 and from flange to flange of the tie and being located immediately beneath and longitudinally of the rails, materially strengthen the tie where the greatest strain occurs. These braces are provided at their ends with 100 lugs 16 and 17, located one above the other, and in the application of the braces the said lugs are passed out through suitable openings in the flanges 11, and said lugs 16 and 17 are then bent in opposite directions to a firm 105 and constant engagement with the outer

faces of the flanges of the tie; the angle at which these lugs or clamps enter the sides of the tie causes the strain to be carried on the lower edges of the clamps in addition to the security obtained by bending them over sidewise, as is clearly shown in each of the views in the drawings.

From the foregoing, it will be observed that bolts and nuts are dispensed with, and 10 that the fastening devices employed are not liable to be disturbed by the jar incident to the passing of rolling stock.

Having thus described our invention, we 15 claim as new and desire to secure by Letters Patent:

1. A metal railway tie having its sides outwardly flared and centrally recessed, a transverse vertical brace at the point crossed by the rail, said brace having lugs at its end, 20 and the sides of the tie being provided with openings through which pass the lugs.

2. A metal railway tie constructed from one piece of metal, having its sides outwardly and downwardly flared and centrally recessed, clamps stamped from the upper face 25 of the tie underneath the rail which are

pressed down on the flange of the rail, and braces connecting the flanges immediately below the rails.

3. The combination of a metal railway 30 tie constructed from one piece of metal, having its sides outwardly and downwardly flared and centrally recessed, being also provided with clamping lugs for the rails, integral with the tie and braces located one 35 below each rail, extending from one side of the tie to the other and from top to bottom, and lugs extending from the ends of the braces, which lugs are passed through the sides of the tie, the lugs at each side being 40 bent in opposite directions and brought to clamping engagement with the flaring sides of tie and inclining downward when so bent.

In testimony whereof we have signed our names to this specification in the presence 45 of two subscribing witnesses.

JAMES R. ROBINSON.
JOHN F. SUGRUE.
